CASEMENT WINDOW STRUCTURE

Albert Lang, Berkeley, Calif.

Application February 28, 1934, Serial No. 713,277

17 Claims. (Cl. 189—69)

The present invention relates to a casement window structure, and more particularly to an improved window structure and arrangement with a screen wherein a window locking means, located 5 outside of the screen, is controllable through and by a flexing of the screen.

An object of the invention is to provide an improvement in a screened casement window wherein in the window locking and controlling means can 10 be operated without removing the screen.

Another object of the invention is to provide a new and novel locking means and screen arrangement for a casement window of the type having an out-swinging sash wherein the locking 15 means can be controlled from the inside of the screen without requiring an opening through or a modification of the screen proper.

Another object of the invention is to provide a flexing screen for a casement window having 20 means adapted to cooperate with a window lock to facilitate an operation of the lock by a flexing of the screen.

Another object of the invention is to provide a new and improved locking means for a casement 25 window sash of the out-swinging type which can be operated to unlock the sash by pressure applied thereto in a sash opening direction.

A further object of the invention is to provide a metal screen with means at its edge which will 30 prevent a sharp bending of the wire mesh forming the screen by a flexing thereof and which will also return the engaging strands of the wire mesh to their normal plane after a flexing of the screen.

With the above and other objects in view, the 35 invention resides in the construction, combination and arrangement of parts substantially as will be hereinafter described and more particularly defined by the appended claims.

For a better understanding of the invention reference should be had to the accompanying 40 drawings wherein there are shown, by way of illustration and not of limitation, preferred embodiments thereof.

In the drawings:

Figure 1 is an inside vertical view of a casement window having two out-swinging sashes with a screen, constructed and arranged in accordance with the invention, disposed thereover.

Figure 2 is a view similar to Figure 1 showing a casement window having a single out-swinging sash with a screen, constructed and arranged in accordance with the invention, disposed thereover.

Figure 3 is a fragmentary view showing one

form of lock engaging means carried by a screen for a window of the type illustrated in Figure 1.

Figure 4 is a view similar to Figure 3 showing a modified form of lock engaging means provided on a screen for use with a single out-swinging sash window of the type illustrated in Figure 2.

Figure 5 is a fragmentary side elevation of the structure illustrated in Figure 4.

Figure 6 is a perspective view of the lock engaging and screen protecting member shown in Figures 2, 3 and 4.

Figure 7 is a modified form of the screen projecting device which is particularly adapted for use with a screen of the type illustrated in Figure 1.

Figure 8 is an enlarged fragmentary sectional view taken along line VIII—VIII of Figure 2, looking in the direction of the arrows.

Figure 9 is an enlarged fragmentary sectional view taken along line IX—IX of Figure 1, looking in the direction of the arrows.

Figure 10 is a vertical fragmentary sectional view taken along line X—X of Figure 2, looking in the direction of the arrows.

Figure 11 is a fragmentary view of a modified 25 form of locking means adapted for use on a casement window of the type illustrated in Figure 1.

Figure 12 is a horizontal sectional view looking down upon Figure 11 and showing a screen disposed thereover.

Figure 13 is a fragmentary vertical sectional view taken along line XIII—XIII of Figure 11, looking in the direction of the arrows.

Figure 14 is a fragmentary vertical view of a modified locking means for an out-swinging 35 sash, and

Figure 15 is a horizontal sectional view taken along line XV—XV of Figure 14, looking in the direction of the arrows.

As illustrated in Figures 1 and 2 of the drawings, the present invention is primarily intended for a casement window of the type having an out-swinging sash or sashes, over which an inside screen may be disposed, and comprises an improved window locking and screen arrangement that will permit an unlocking and an opening of the window without the removal of the screen.

In Figure 1, the casement window is shown as having two out-swinging sashes 10 which carry individual locking means 11 and close upon a dividing bar or meeting rail 12. Disposed over the two out-swinging sashes 10, the locking means 11 and the dividing bar 12, there is a metal wire screen 13. The screen 13 is carried by a screen

frame 14 that can be conveniently secured over the window opening, in spaced relation with the inside of the out-swinging sashes 10, by any suitable means. Each of the out-swinging sashes 10 is arranged to be opened and closed by an operating mechanism 15 which projects beneath the screen frame 14 and connects with the bottom thereof. These operating mechanisms may be of any convenient form. As shown, the operating mechanism 15 comprises a crank 16 that controls a lever (not shown) which is slidably connected to the bottom of the out-swinging sashes 10, as is well understood in the art. While the window operating mechanism 15 is capable of opening and closing an associated out-swinging sash 10, it is necessary to also provide means which will lock the out-swinging sash in its closed position. This is provided for in the present instance by the locking means 11 which operates as will be hereinafter pointed out.

The arrangement illustrated in Figure 2 of the drawings is similar to that described above, except that the window is provided with a single out-swinging sash 17 having a locking means 18 mounted thereupon opposite its hinged side. The out-swinging sash 17, like the out-swinging sashes 10, also has an operating mechanism 15 which is controlled by a crank 16. In this figure of the drawings the out-swinging sash 17 is shown as having a wire screen 19 supported thereover by a screen frame 20 which can be mounted in any suitable manner upon the window casement.

Where a metal screen has been used in a casement window of the character contemplated by this invention, it has been necessary to either modify the screen structure or provide some special mechanism whereby the window locking means, such as the locking means 11 and 18 referred to above, could be operated without removing the screen from the window. This has been accomplished, in the past, by controlling the window locking means with an operating mechanism which extends beneath the screen frame in the same manner as does the sash operating mechanism 15, or by projecting a lock operating handle through an opening in the screen, or through the screen frame, as illustrated in United States Patent, Number 1,780,823, 50 issued November 14, 1930, to Paul G. Johnson.

In accordance with the present invention, the sash locking means 11 and 18 have respectively operating handles 21 and 22 which extend out from the out-swinging sashes to a point closely adjacent or in actual engagement with the outside of their respective covering screens 13 and 19. These operating handles 21 and 22 are also arranged so that they will move in an outward sash opening direction to unlock or release the sash locking means 11 and 18 when pressure is applied thereto from the inside of the screens 13 and 19. With a sash lock operating in this manner it is possible, by properly locating the wire mesh of the screens 13 and 19, to accomplish an unlocking of the out-swinging sashes with a slight flexing of the screens by pressure applied to the inside thereof and against the operating handles 21 and 22.

As shown in Figure 1 of the drawings, the lock operating handles 21 project upwardly and inwardly from the sash locking means 11 and into close proximity with the screen 13 so that a lock releasing force may be applied thereto, immediately over their outer ends, through and by a flex-

ing of the screen 13. In order to indicate the points at which pressure should be applied to the screen 13 to release one or the other of the locking means 11, the screen 13, as illustrated in Figure 3 of the drawings, is provided with two disc-like members 23. These disc-like members 23 are mounted against the inside of the screen 13 and are secured thereupon by means of a number of tabs 24 which project through and interlock with the wire mesh forming the screen. 10 If desired these disc-like members 23 may be provided with a suitable legend, as for instance, "Press here" or "Push to unlock". For the purpose of preventing wear on the screen by frequent contact with the operating handles 21, 15 similar disc-like members (not shown) may also be secured to the outside of the screen opposite the disc-like members 23. In the arrangement shown, the operating handles 21 are spaced so as to permit a flexing of the screen sufficient to 20 operate one of the handles 21 without causing an operation of the other handle. This makes possible an unlocking of either one of the sashes without an unlocking of the other sash.

Where the locking means is disposed substantially at the middle of the screen, no special precaution need be taken to insure against a breaking of the wire mesh of the screen as the result of a frequent flexing thereof. However, where the sash locking means 18 is located near 30 one edge of the screen, as illustrated in Figure 2 of the drawings, some precaution should be taken to insure against a too abrupt bending of the wire mesh where it is secured to the screen frame. With this arrangement, it will be readily seen that, should the screen 19 be flexed outwardly by pressure applied at the end of the operating handle 22, the wire mesh will be subjected to an abrupt bending which in time would result in a breaking thereof where it engages the 40 frame 20. In order to overcome this difficulty, the frame 20 is provided with a flexible reinforcing member 25 which extends outwardly beneath the screen and over the end of the operating handle 22.

As shown in Figures 4, 5 and 6 of the drawings, the flexible reinforcing member 25 has a rounded shoulder portion 26, over which the screen mesh is stretched. Because of its flexibility, the member 25 will yield with the screen when it is 50 flexed and thus prevent a sharp bending of the wire mesh where it engages the frame 20. The extending end of the flexible reinforcing member 25 has a button-like member 27 secured thereupon, against which pressure may be applied to 55 move the operating handle 22 in a lock operating direction. The button-like member 27 is shown as extending through to the inside of the screen 19 so that it serves to locate the point at which pressure should be applied to unlock the window. 60

In addition to providing against a too abrupt bending of the wire mesh forming the screen, the flexible reinforcing member 25, because of its rounded shoulder 26 and flexible character, will also maintain the horizontal strands of the wire mesh disposed thereover in a taut condition and in their normal plane. As a further means to insure a tautness in the flexing portion of the screen, there is shown a second flexible member 28 which is secured to the screen frame 20 directly opposite and in line with the flexible reinforcing member 25. The flexible member 28, like the flexible reinforcing member 25, has a rounded shoulder, designated by the numeral 29, which serves to prevent a sharp bending of the 75

screen wires at the frame. In the case of a screen arrangement, as illustrated in Figure 1 of the drawings, it may be desirable to provide two flexible members 28, one at each side of the 5 screen frame and in line with the operating handles 21.

10 While the individual wires forming the screens 13 and 19 are illustrated in Figures 1, 2 and 10 of the drawings as extending diagonally, it should be stated that this is not the normal disposition of the wires. A diagonal showing of the screen forming wires is made, in the drawings, for the purpose of avoiding a confusion of the lines defining the screen with the lines which define 15 the other elements illustrated. It is to be understood, however, that the disposition of the wires of the mesh forming the screens is immaterial as screen cloth cut on a bias can be successfully used with this invention.

29 From the foregoing it will be seen that the location of the sash locking means beneath the screen is also immaterial. The locking means may be disposed centrally of the screen, as in Figure 1 of the drawings, or adjacent one side
25 of the screen, as in Figure 2 of the drawings. In order that the locking means may be controlled as contemplated by this invention, it is desirable that the locking means be constructed so as to render an operation thereof possible by pressure applied through a flexing of the screen. Where the locking means is carried by the out-swinging sash, it is necessary that its operation be controlled by an outward window opening pressure. While this form of locking means is
30 to be preferred, even when the locking means is mounted upon a stationary portion of the window casement, as upon the sash dividing bar shown in Figure 1 of the drawings, it will be apparent that the locking means may be operated
35 by a reverse direction of movement, as by an outward flexing of the screen. In other words, it is conceivable that the screen can be provided with a means which will engage the lock operating handle and impart an unlocking movement thereto as the result of an inward pull exerted upon the screen adjacent the end of the lock operating handle.
40
45

Reference is now made to the remaining figures of the drawings wherein there are illustrated preferred lock structures and arrangements in which the operation of the locking means is controlled by an outward pressure exerted through and by an outward flexing of the screen.

In Figure 8 of the drawings, the out-swinging sash 17 is shown as closed upon a casement 30 which is set in a wall 31. The casement 30 has a screen frame 29 secured upon the inside thereof so as to support the screen 19 over the lock operating handle 22. The locking means 18 is illustrated as comprising a support 32 having a horizontally disposed shaft 33, the end of which is bent outwardly to form a detent 34 at the end thereof. The operating handle 22 is fixed upon the shaft 33 so that when pressure is applied thereto the detent 34 will be forced down and out of engagement with an abutment 35, carried by the casement 30, to thus permit the out-swinging sash 17 to be freely opened by its operating mechanism 15.

70 In Figure 10 of the drawings, the detent 34 is shown as so located with respect to the abutment 35 that it will clear the latter when the operating handle 22 is pressed outwardly. In order to hold the detent 34 in its normal locking position, there is provided, about the shaft 33, a

spring 36 which operates to bias the detent 34 into its upper or locking position. This spring 36 also holds the operating handle 22 in its outermost position against or adjacent the outside of the screen 19.

With the above described arrangement it will be seen that, when pressure is applied to the button-like member 27, the flexible reinforcing member 25 will be flexed outwardly with the screen and that, when the operating handle 22 is engaged thereby, the detent 34 will be moved downwardly so as to clear the abutment 35. As soon as the detent 34 clears the abutment 35, the out-swinging sash 17 will be moved outwardly a slight distance and as a result the detent 34 will be prevented from again moving into locking engagement with the abutment 35. After the detent 34 has been thus moved, the out-swinging sash 17 may be partially or fully opened by its operating mechanism 15. It will be seen that the pressure exerted upon the operating handle 22, in addition to rendering the locking means 18 inoperative, also functions to slightly displace the detent 34 with respect to the abutment 35 and render the locking means inoperative until the out-swinging sash 17 is again closed by its operating mechanism 15.

In Figure 9 of the drawings, the locking means is constructed in substantially the same manner as has been disclosed by the showings made in Figures 8 and 10 of the drawings. As here shown, the two out-swinging sashes 19 close upon a meeting rail or dividing bar 12 which carries abutments 37 that cooperate with detents 34 provided upon the locking means 11, as is the case in the locking means 18 described above. In this showing, the screen 13 is provided with disc-like members 23 to indicate and locate the point at which pressure should be applied to engage the operating handles 21. 40

In Figures 11, 12 and 13 of the drawings, there is shown an arrangement for a double sash window wherein two opposed out-swinging sashes 38 close upon a meeting rail or casement dividing bar 39. The sash locking means in this instance comprises a pair of oppositely spaced supports 40 having a horizontal shaft 41 disposed there between, upon which there is mounted right and left hand locking members 42 having upwardly and outwardly projecting operating handles 43. The locking members 42 have outwardly projecting portions forming detents 44 which extend through the flanges of the dividing bar 39 and cooperate with abutments 45 carried by the out-swinging sashes 38. Because of the immovable disposition of the locking means, it is necessary that the detents 44 be constructed so as to hook under the abutments 45. Therefore, in order that the detents 44 may operate to snap into locking engagement with the abutments 45, the ends thereof are chamfered as at 46. This arrangement requires that an initial opening movement be imparted to the out-swinging sashes 38 before the pressure upon the operating handles 43 can be released. This is in contradistinction to the arrangement described in connection with Figures 8, 9 and 10 of the drawings, wherein the lock releasing pressure applied to the operating handles also functions to impart an initial opening

movement to the out-swinging sashes and renders the sash locking means inoperative without requiring the continuance of a pressure upon the operating handles. However, it will be possible to provide for an initial opening of the out-swinging sashes 38. For instance, it is conceivable that

a projection, as shown in dot and dash lines at 47 in Figure 12 of the drawings, may be formed on the outside of the operating handles 43. If such a projection is provided, it should be of a length sufficient to engage the adjacent out-swinging sash 38 as soon as the detent 44 thereof has moved out of engagement with its cooperating abutment 45. It is also conceivable that this initial sash opening movement may be accomplished by providing an abutment engaging projection upon the detent 44, as illustrated by dot and dash lines at 48 in Figure 13 of the drawings. Such a projection 48 would exert an outward pressure upon the abutment 45 and move it and the out-swinging sash 38 sufficiently to clear the detent 44.

In view of the fact that the out-swinging sash locking means, described above, contemplates a coaction between a vertically stationary abutment and a substantially vertically movable detent, it is necessary, because of the tendency of an out-swinging sash to sag, to provide a means between the stationary casement frame and the meeting edge of the sash which will properly position the sash with its locking detent or abutment in cooperation with the associated abutment or locking detent upon the casement. This can be accomplished in a number of ways. A preferred arrangement is to provide a horizontally disposed projection 49 upon the casement frame and a fixture, upon the sash, having a horizontally disposed groove 50 with which the projection 49 will cooperate. It is to be understood, however, that the position of the projection 49 and the groove 50 may be reversed. The groove 50 may be mounted upon the frame and the projection 49 may be provided upon the out-swinging sash.

In Figures 14 and 15 of the drawings, there is illustrated a modified form of the invention where in an out-swinging sash 51 is shown as held in its closed position against a casement 52 by means of a spring 53 having a latching abutment 54 which overlaps the casement frame 52. The spring 53 is shown as secured upon the web of the out-swinging sash 51 and as projecting inwardly toward an overlying screen 55 where it is bent parallel therewith to form an operating handle 56. The operation of this embodiment of the invention is believed to be self evident and, therefore, a description of its operation should be unnecessary.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves, in view of this broad disclosure, to persons skilled in the art. It is believed that this invention is broadly new and it is desired to claim it as such so that all changes as come within the scope of the appended claims are to be considered as part of this invention.

Having thus described my invention, what I claim and desire to secure by Letters Patent is—

1. A casement window structure comprising a frame, an out-swinging sash mounted upon said frame, an inside screen disposed over said out-swinging sash, and a locking means for holding said out-swinging sash in its closed position, disposed beneath said screen and operable to unlock the out-swinging sash by pressure applied thereto by a flexing of said screen in a window opening direction.

2. A casement window structure comprising a frame, an out-swinging sash mounted upon said frame, an inside screen disposed over said out-swinging sash, a locking means for said out-swinging sash adapted to automatically lock said out-swinging sash in its closed position, and means operable to unlock said out-swinging sash when pressure is applied thereto in a window opening direction, said last means being disposed in co-operating relation with said screen, whereby it can be operated by an outward flexing pressure applied to the screen.

3. A casement window structure comprising a frame, an out-swinging sash mounted upon said frame, a screen mounted upon said frame over said out-swinging sash, and a locking means mounted upon said out-swinging sash beneath said screen adapted to be rendered inoperative by pressure applied thereto in a window opening direction by an outward flexing of said screen.

4. A casement window structure comprising a frame, an out-swinging sash mounted upon said frame, a lock adapted to automatically lock the window in its closed position, an inside screen disposed over said out-swinging sash and said lock, and means for unlocking said lock operable by pressure applied upon and by a flexing of said screen in a window opening direction.

5. A casement window structure comprising a frame having a dividing bar extending there across, oppositely disposed out-swinging sashes closing upon said dividing bar, individual locking means for said out-swinging sashes, and an inside screen disposed over said out-swinging sashes and said individual locking means, said locking means being disposed in cooperating relation with said screen and operable to unlock said out-swinging sashes when said screen is flexed outwardly by pressure applied thereto in a window opening direction.

6. A casement window structure comprising a frame having a dividing bar extending there across, oppositely disposed out-swinging sashes closing upon said dividing bar, individual locking means for said out-swinging sashes mounted upon the dividing bar, said locking means being independently operable to unlock said out-swinging sashes by pressure applied thereto in a window opening direction and a screen disposed over and in cooperating relation with said locking means, whereby said locking means may be independently operated to unlock said sashes by applying a flexing pressure upon said screen.

7. A casement window structure comprising a frame having a dividing bar extending there across, oppositely disposed out-swinging sashes closing upon said dividing bar, individual locking means carried by each of said out-swinging sashes, and an inside screen disposed over said out-swinging sashes and said individual locking means, each of said locking means being operable independently to unlock said out-swinging sashes by pressure applied upon and by a flexing of said screen in a window opening direction.

8. A casement window structure comprising a frame, an out-swinging sash, an inside screen disposed over said frame and out-swinging sash, a lock for securing said out-swinging sash in its closed position disposed outside of said screen, and means for controlling said lock operable by pressure exerted upon and by an outward flexing of said screen.

9. A casement window structure comprising a frame, an out-swinging sash, an inside screen disposed over said frame and out-swinging sash, a

locking means carried by said out-swinging sash disposed outside of said screen, and means for controlling said locking means extending to a point adjacent said screen and operable to unlock said out-swinging sash by pressure exerted upon and by a flexing of said screen.

10. A casement window structure comprising a frame, an out-swinging sash, an inside screen disposed over said frame and out-swinging sash, a locking means mounted upon said frame for securing said out-swinging sash in its closed position disposed outside of said screen, and means extending to a point adjacent said screen for controlling said locking means and operable to unlock said out-swinging sash by pressure exerted upon and by an outward flexing of said screen.

15. A casement window structure comprising a frame, a dividing bar extending across said frame, oppositely disposed out-swinging sashes closing upon said dividing bar, an inside screen disposed over said frame, said dividing bar and said out-swinging sashes, individual locking means for securing said out-swinging sashes in their closed positions disposed outside of said screen, and means for controlling said locking means independently operable by pressure exerted upon and by an outward flexing of said screen.

20. A casement window structure comprising a frame, a dividing bar extending across said frame, oppositely disposed out-swinging sashes closing upon said dividing bar, an inside screen disposed over said frame, said dividing bar and said out-swinging sashes, locking means mounted upon said dividing bar for independently securing said out-swinging sashes in their closed positions, and means for independently controlling said locking means operable by pressure exerted upon and by an outward flexing of said screen.

25. A casement window assembly unit comprising a frame for positioning in a wall opening, an out-swinging sash on the frame, a window lock for securing said out-swinging sash in its closed position comprising a locking member and an operating handle, and an inside screen disposed over said out-swinging sash and operating handle, the disposition of said operating handle being such that it can be operated to unlock the out-swinging sash by pressure applied thereto by a slight outward flexing of the screen.

14. In a casement window structure, the combination of a frame for positioning in a wall opening, said frame having a dividing bar, out-swinging sashes mounted on the frame and closing on said dividing bar, a multiple sash lock mounted on the dividing bar and operative from the inside of the frame, an inside screen disposed over said dividing bar and said multiple sash lock, and independent operating means for said multiple sash lock projecting outwardly from said dividing bar and terminating closely adjacent said screen, whereby said operating means may be independently actuated by pressure applied thereto by an outward flexing of the screen.

15. A casement window structure comprising in combination, an out-swinging sash, an inside screen disposed over said out-swinging sash, a lock located outside of said screen for securing said out-swinging sash in its closed position, and an operating means for actuating the lock extending into cooperating relation with the screen, whereby it may be operated by a flexing of the screen substantially as described.

16. In a casement window, the combination of an out-swinging sash, a locking member for retaining said out-swinging sash in its closed position adapted to be rendered inoperative by pressure applied thereto in an outward direction, a screen disposed inside of said out-swinging sash and over said locking member, a frame for supporting said screen in a plane closely adjacent said locking member, and means carried by said screen located immediately over said locking member against which pressure may be applied to flex the screen and render said locking member inoperative.

17. In a casement window, the combination of an out-swinging sash, a locking member for retaining said out-swinging sash in its closed position, an operating handle adapted to render said locking member inoperative when pressure is applied thereto, a screen disposed inside of said out-swinging sash, a frame for supporting said screen closely adjacent said operating handle, and means carried by said screen against which pressure may be applied to actuate said operating handle.

ALBERT LANG.
